WILLIAM L. BARRON, OF NEW YORK, N. Y., AND FRITZ E. OSOL, OF ELIZABETH, NEW JERSEY, ASSIGNORS TO THE SINGER MANUFACTURING COMPANY, A CORPORATION OF NEW JERSEY.

STOP-MOTION DEVICE FOR SEWING-MACHINES.

1,244,458.

Specification of Letters Patent. Patented Oct. 30, 1917.

Application filed February 13, 1914. Serial No. 818,441.

To all whom it may concern:

Be it known that we, WILLIAM L. BARRON and FRITZ E. OSOL, citizens of the United States, residing at New York, in the county 5 of New York and State of New York, and Elizabeth, in the county of Union and State of New Jersey, respectively, have invented certain new and useful Improvements in Stop-Motion Devices for Sewing-Machines, 10 of which the following is a specification, reference being had therein to the accompanying drawings.

This invention relates to improvements in stop-motion devices for that class of sewing 15 machines adapted to produce detached groups of stitches in which means are employed for automatically stopping the machines at the completion of each stitching group.

20 The invention has for its primary object to provide means for controlling the start- and stop-motion lever in such manner that after the machine has been started by actuation of a treadle device its automatic stopping is insured, the treadle device being rendered ineffective until the stop-motion lever moves into stopping position.

The invention comprises the usual spring-pressed start- and stop-motion lever, which 30 supports a plunger adapted to engage a cam-disk on the main-shaft of the machine when the lever is automatically tripped by a stopping cam-wheel. The stop-lever is returned to starting position by means of a 35 shifting lever, operated by a treadle, through the intermediary of a link-member. The link-member is formed in two sections, the lower section being provided with a socket to receive a spring-pressed plunger comprising the upper section, the two sections being 40 normally locked together by means of a latch-lever. When the treadle is depressed to start the machine the sectional link-member is carried downward thereby rocking the 45 shifting lever, which throws the stop-lever into starting position. At this point a spring-pressed latch acts to hold the stop-lever until it is automatically released at the end of a stitching cycle.

50 In machines of high speed, for producing groups of tacking stitches and the like, only a few seconds elapse between the starting of the machine and the completion of one stitching cycle, and it frequently happens

that the operator, by continuing to hold the 55 treadle depressed, prevents the stop lever from moving into stopping position at the normal period, which results in defective work, and, in button sewing, the breakage of needles. In the present improvements, 60 continued pressure upon the treadle after the stop lever has been moved to starting position will separate the sections of the link-member by the tripping of the latch which serves to normally hold said members in 65 fixed relation to each other, and the treadle remains wholly ineffective until the machine is stopped by the automatically effected throw of the stop lever.

In devices of the present type, the operator may depress the treadle sufficiently to start the machine and yet insufficiently to permit the stop-lever detent to lock into place. In such case the stop-lever will 70 spring back into stopping position, and the machine will be prematurely stopped. When the lateral throw of the stop-lever is used to impart a final thread-severing movement to a cutter operated in part by a cam, as described in Patent No. 807,676 of December 80 19, 1905, the premature overthrow of the stop-lever may break or disarrange the cutter mechanism. To avoid such result, the present invention includes means whereby, 85 in the case of such partial retraction of the stop-lever, an eccentrically-mounted disk or cam-lever will project into the path of the rotating cam-disk on the main-shaft and will serve to impart sufficient movement to the stop lever to permit its latch to lock into 90 place.

In the accompanying drawings, Figure 1 is a front perspective view of the improvements applied to a sewing machine, and Fig. 2 is a perspective view from the rear of the 95 improvements. Fig. 3 is a plan view, and Figs. 4, 5 and 6 are detail perspective views, showing certain parts of the improvements.

The improvements are shown applied to a sewing machine provided with a driving 100 shaft 1 on which is mounted the helical gear-wheel 2 meshing with gear-wheel 3 which serves to transmit motion to stopping cam 4 on the transverse shaft 5. The driving shaft 1 is provided near its end with the loose pulley 6 and the fast pulley 7 (shown in dotted lines) the fast pulley having rigidly attached thereto a stop-motion cam 8.

Secured to the upright portion A of the bracket-arm is a supporting bracket 9 provided with a slotted outwardly-projecting boss 10 adapted to receive a cylindrical block 11 provided with a longitudinal slot within which the stop-lever 12 is pivotally supported, the arrangement being such that the stop-lever may rock laterally within boss 10 in addition to its forward and rearward movement. The stop-lever is provided with the usual spring-pressed plunger 12^x adapted to engage cam-disk 8 on the main-shaft, and with the belt-shifting fork 8. The stop-lever is pressed forwardly toward stopping position by means of a plate spring 13 secured at its lower end between a bracket 14 and the bed-plate of the machine, the tension of spring 13 being regulated by an adjusting screw 15 on the bracket.

20 The stop-lever is held in its rearward or starting position by means of a detent-lever 16 fulcrumed at 17 upon the supporting bracket 9 and pressed toward latching position by means of spring 18, its hook 16^x being adapted to engage a tooth 19 on the stop-lever. At the end of one stitching cycle a tripping point 20 carried by the stopping cam 4, comes into contact with the rear end of detent-lever 16, which causes the release of the stop-lever which is thrown forwardly into stopping position, the action of the belt-shifting fork 8 moving the driving belt from the fixed pulley 7 to the loose pulley 6, and the lateral overthrow of the stop-lever serving to impart movement to cutter-actuating bell-crank 21 in a manner well known.

25 The supporting bracket 9 is provided at its upper end with the spaced projecting arms 22 between which is fulcrumed by means of stud-bolt 23 a shifting lever 24 provided with an arm 25 which engages the stop-lever 12 and is adapted to move the same to starting position when the shifting lever is operated. A nose 26 on the shifting lever is engaged by the head of a screw 27 on the stop-lever when the latter springs forwardly to stop the machine, whereby part of the shock of such movement is taken up 30 by the shifting lever and the latter is held against upward movement.

35 The shifting lever 24 is operated by a treadle device through the intermediary of a link-member formed in two sections, 28 and 29. The upper link-section 28 is a plunger pin fitted within the tubular portion 29^x of member 29, and provided at its end with a hook to engage the outer end of the shifting lever. A coiled spring 30 surrounding the plunger pin 28 and interposed between a collar 31 thereon and the socket portion 29^x of link-section 29 tends to press the two link-sections apart, an action which is normally resisted by a latch-lever 32 fitted within a slot 33 formed in link-

section 29 and fulcrumed at 34. Latch-lever 32 is provided with an angular end 32^x which is adapted to engage the annular shoulder or flange 31^x of collar 31 under the action of a spring 35, one end of which is secured to the rearwardly projecting arm 36 of the latch-lever and the opposite end of which is clamped under the head of a screw 37 secured to link-section 29.

30 The link-member is connected to a treadle rod 38, the hook end of said rod being received in a slot 39 formed in the lower end of link-section 29 and held in place therein by means of a pin 40 provided with annular grooves 41, 41^x to receive the free end of a detent-spring 42, fitted within a slot 43 in the said link-section 29 and having one end clamped under the head of a screw 44. With one exception the walls of grooves 41, 41^x are slightly beveled so that the detent-spring will not offer sufficient resistance to prevent the withdrawal of pin 40 from slot 39 when it is desired to remove the treadle rod. However, complete withdrawal of pin 40 is prevented by the action of the detent-spring on the angular outer wall of groove 41.

35 It will be seen that downward movement of the treadle rod and the sectional link-member 28, 29 will operate shifting lever 24 to shift the stop-lever from stopping position (Fig. 1) to starting position (Fig. 2). By continuing to depress the treadle the operator will carry the rearwardly extending arm 36 of latch-lever 32 into contact with a tripping finger 45 adjustably secured to stop-lever 12, whereby the angular end 32^x of the latch-lever will be retracted from shoulder 31^x of collar 31 and link-section 28 will be given a slight upward movement by the action of spring 30. It will be seen that the action of latch-lever 32 in uncoupling the link-sections 28, 29 will free the shifting lever 24 and will render the treadle ineffective. At this point further downward movement of link-section 29 is prevented by the contact of its stud 46 with the base of a guide-slot 47 formed in the bracket-member 48 having its foot 49 secured by means of screws 50 to the lower end of the stop-lever, the member 48 being embraced by the spaced ears *a* of the said link-section 29.

40 When the stop-lever springs into stopping position at the end of a stitching cycle, the head of screw 27 will engage nose 26 of the shifting lever, and the latter, together with link-section 28 will be held firmly against upward movement. Now when the treadle is released a coiled spring 51 secured at one end to the stop-lever 12 and at its opposite end to link-section 29 will move the latter upwardly until latch-lever 32 engages shoulder 31^x on collar 31 and the two link-sections are locked together.

45 As heretofore stated, the operator may de-

press the treadle sufficiently to start a machine of the type described and yet insufficiently to permit the detent-lever 16 to lock the stop-lever in place, causing the latter to 5 spring back into stopping position when the shifting lever is released and before the end of the stitching cycle. To avoid such result, stop-lever 12 is provided at its upper end with a bracket 52 secured in position 10 by means of screw 53 and formed with an aperture to receive a stud-screw 54 which pivotally supports an eccentrically mounted disk or cam-lever 55 disposed adjacent plunger 12* and projecting slightly beyond 15 the face of the latter. When the stop-lever is retracted sufficiently to carry the plunger out of the path of the rotating cam-disk 8 but insufficiently to permit detent-lever 16 to lock in place, the rotating cam-disk 8 will 20 swing the cam-lever on its pivotal support whereby the stop-lever will be given a slight rearward movement until it is seized by the detent-lever. A coiled spring 56 surrounding stud-screw 54 and having one end 25 secured to bracket 52 and its opposite end secured to cam-lever 55 serves to maintain the latter normally in retracted position. And the bracket 52 is provided with an adjusting screw 57 against which the cam-lever 30 rests and by means of which its retracted position may be adjusted.

It will be understood that the construction of sectional link-member 28, 29 and of other parts of the improvements may be greatly 35 modified within the scope of the invention, it being manifest that the same is not limited to the precise embodiment thereof herein shown and described.

Having thus set forth the nature of the 40 invention, what we claim herein is:—

1. In stop-motion mechanism for sewing machines, the combination with a spring-pressed start- and stop-motion element, of a latch for locking said element in starting 45 position in opposition to its spring, automatic tripping means for said latch, a shifting device for said start- and stop-motion element, and means adapted to render said shifting device inoperative to prevent the 50 automatic stopping of the machine after the start- and stop-motion element is locked in starting position.

2. Stop-motion mechanism for sewing machines comprising, in combination, a 55 spring-pressed start- and stop-motion lever, a latch for locking said lever in starting position in opposition to its spring, automatic tripping means for said latch, a shifting device and operating means therefor includ- 60 ing two relatively movable link-sections connected to said shifting device, a spring reacting against both link-sections, a locking member adapted to normally lock the link- sections in fixed relation to each other, and 65 means for unlocking the link-sections as

said lever is moved to starting position, whereby said last mentioned spring may take up part of the shock of the stop-lever in springing to stopping position.

3. In a sewing machine, in combination, a 70 spring-pressed start- and stop-motion lever, automatic tripping means therefor, a shifting element for moving said lever to starting position, a manually operated element, relatively movable link-sections connecting 75 said elements, a locking device adapted to normally lock said link-sections together, means whereby movements of said manually operated element unlocks said link-sections after said lever has been shifted to 80 starting position, and means whereby said manually operated element may be shifted at will without locking said link-sections together while the machine is in operation.

4. In a sewing machine, in combination, a 85 spring-pressed start- and stop-motion lever, a latch for holding said lever in running position, a shifting element having a lost-motion connection with said lever while said lever is in running position, means 90 whereby said lost-motion is taken up upon movement of said lever to stopping position, manually operated means for actuating said shifting element including relatively movable sections, a spring-latch for locking said 95 sections together, and a stop for tripping said latch.

5. In stop-motion mechanism for sewing machines, the combination with a spring-pressed start- and stop-motion lever, of a 100 latch for locking said lever in starting position in opposition to its spring, automatic tripping means for said latch, a shifting lever for the stop-lever, a plunger-rod connected to the shifting lever, a socket-member 105 adapted to receive said plunger-rod, an operating rod connected to said socket-member, a latch-lever adapted to lock together the plunger-rod and the socket member, and a tripping finger adapted to engage said 110 latch-lever at a predetermined period during the movement of said operating rod.

6. In stop-motion mechanism for sewing machines, the combination with a spring-pressed start- and stop-motion lever, of a 115 shifting lever and an operating rod therefor, relatively movable link-sections connecting the shifting lever and its operating rod and including a socket-section and a plunger-rod fitted therein, a latch-lever adapted 120 to normally lock the link-sections in fixed relation to each other, a tripping finger adapted to engage said latch-lever at a pre-determined period, a stop device for said socket-section, and a spring adapted to return said socket-section to its normal position when said operating rod is released.

7. In stop-motion mechanism for sewing machines, the combination with a spring-pressed start- and stop-motion lever adapt- 130

ed to engage a rotating cam-disk of a shifting device for said stop-lever, a latch for locking said stop-lever in starting position in opposition to its spring, and means adapted to be operated by said cam-disk to impart a movement to the stop-lever, when the latter is shifted to starting position but insufficiently to permit its latch to lock into place.

10 8. In stop-motion mechanism for sewing machines, the combination with a spring-pressed start and stop-motion lever adapted to engage a rotating cam-disk, of a shifting device for said stop-lever, a latch for locking said stop-lever in starting position in opposition to its spring, and a cam-lever carried by the stop-lever in position to be engaged by said rotating cam-disk when the stop-lever is shifted to starting position but insufficiently to permit its latch to lock into place.

9. A stop-motion mechanism for sewing machines, the combination with a spring-pressed start- and stop-motion lever adapted to engage a rotating cam-disk and a latch for locking said stop-lever in starting position in opposition to its spring, of manually operated means for imparting an initial movement of the stop-lever toward starting

position, and automatically acting means adapted to impart a final shifting movement to the stop-lever to complete its movement into starting position.

10. In stop-motion mechanism for sewing machines, the combination with a rotating cam, a spring-pressed start- and stop-motion lever adapted for engagement with the same, and a latch for locking said stop-lever retracted from operative relation with the cam, of a shifting lever, a link-member connected with the same at one end and having at the other end a recess, a treadle-rod having an eyed end entering said recess of the link-member, a retractable pivotal pin crossing said recess of the link-member and entering the eye of the treadle-rod and being provided with spaced shoulders, and a spring detent adapted for engagement with either of said shoulders of the pivotal pin for retaining it in operative or retracted position.

In testimony whereof, we have signed our names to this specification, in the presence of two subscribing witnesses.
